a corporation of Delaware

Application March 14, 1947, Serial No. 734,681

7 Claims. (CL 259—180)

1

My invention relates to a method of and apparatus for classifying small pieces of solid material having unequal size.

From one broad aspect, my invention relates to a classifying system to which is admitted a charge formed from pieces of solid material which have been stratified to form a pattern conforming with gradation in size of the constituent pieces of material. This charge of material, in the classifying system, is separated into streams of material each having, upon passage from said system, substantially the same range of size distribution as regards the pieces of solid material. More particularly, resulting from the aforesaid operation, the total charge of material is apportioned so that the respective streams thereof contain substantial equal quantities of material.

In accordance with a preferred application of the invention, the aforesaid classifying system comprises a grate-like structure formed from rows of passages which are traversed by the charge of stratified material. As hereinafter particularly described, these passages, in adjacent rows thereof, are arranged in staggered or offset relation and, in a selective manner, groups thereof are connected, respectively, to a plurality of pipes or other passage-forming members forming the outlet from the classifying system. Responsive to passage of the material through the described system, the respective streams thereof which traverse the aforesaid pipes are caused to have the characteristics referred to above as regards size distribution and quantity of the pieces of material.

From an important aspect of the invention, the solid material hereinbefore referred to as existing in small pieces having unequal size is such as is known in the art as "contact material" which, in known manner, circulates continuously through a closed system comprising vertical reaction and regenerating zones. Contact material which is thus utilized, for a reason hereinafter described, is formed from pieces of material having standard dimensions ranging down to fines, and in the aforesaid zones, such material gravitates downwardly in moving bed fashion. It is a feature of the invention that, in a vertical housing defining a reaction, regenerating or equivalent zone, utilization of my novel classifying system improves uniformity of distribution of the contact material, as regards size of the pieces thereof, in planes extending horizontally through such a housing at different respective levels, such improvement being advantageous for the reasons hereinafter described.

2

Various other objects and advantages of my invention will become apparent from the following detailed description.

My invention resides in the classifying system, method steps, apparatus and combinations of the character hereinafter described and claimed.

For an understanding of my invention and for an illustration of one form and one application thereof, reference is to be had to the accompanying drawings, in which:

Fig. 1 is an elevational view, partly in section, showing my novel classifying system as incorporated in a system traversed by circulating contact material;

Fig. 1a is an horizontal sectional view, partly in plan, taken on the line 1a—1a of Fig. 1;

Fig. 2 is a longitudinal sectional view, partly in elevation, showing my novel classifying system;

Fig. 2a is a perspective view, partly broken away, illustrating a detailed feature of the invention;

Fig. 3 is a transverse, vertical sectional view, partly in elevation, taken on the line 3—3 of Fig. 2;

Figs. 4 and 4a are plan views as viewed from the line 4—4 of Fig. 2;

Figs. 5 and 6 are longitudinal sectional views, partly in plan, taken on the lines 5—5 and 6—6 of Fig. 2; and

Fig. 7 is a perspective view showing parts of my classifying system in disassociated relation.

For the purposes of explanation, I have illustrated and described my invention in connection with an important application which, as hereinbefore stated, relates to passage of contact material downwardly through a housing. Thus, in Fig. 1, A represents such a housing which is traversed by gravitating contact material B having thereon a carbonaceous deposit which, for regenerating purposes, is burned when a suitable regenerating medium such as air is admitted to said housing A in suitable manner, as by a plurality of spaced engagers C, the resulting flue gases being withdrawn from the housing A by

40 a plurality of spaced disengagers D. Regenerating arrangements of the character described are well known and, in connection therewith, it shall be understood that the engagers C and disengagers D may be of any suitable character, for example, as known in the art.

Any suitable arrangement may be utilized for continuously discharging the regenerated contact material from the housing A. To this end and as diagrammatically indicated, a plurality of 55 spaced horizontal tube sheets E may be secured

to the interior surface of the lower end portion of the housing A, the extreme lower portion of which, preferably, is conical as illustrated. A plurality of suitably spaced tubes or pipes F open through and depend from each of the tube sheets E. As known in the art, the tubes F on successively lower tube sheets progressively decrease in number and the diameter thereof progressively increases whereby the contact material passes through the lower conical end portion of the housing A and reaches a main discharge pipe or conduit G from which said contact material is passed to an elevator and then to a reaction zone, not shown. After passage through the reaction zone, the spent contact material passes by way of a conduit H to the lower end of an elevator I by which said contact material is raised to an upper level for subsequent gravitating passage through a pipe or conduit J from which, in the manner hereinafter described, it is admitted to the aforesaid housing A.

Contact material of the character referred to above is usually catalytic in character such, for example, as activated clay pellets, synthetic silica-alumina pellets or beads etc., having suitable major dimensions which may range upwardly to $\frac{1}{4}$ inch, $\frac{1}{2}$ inch or more. In operation, this contact material circulates continuously through the system comprising the regenerating and reaction housing. Therefore, even though of standard dimensions when admitted to the system, it results, due to attrition during continued operation, that gradation in size of the contact material occurs. Hence, normally, during such continued operation, the size of the contact material ranges downwardly from that which is of standard dimensions to mere dust-like particles or fines which, to substantial extent, along with smaller sub-standard pieces form a part of the circulating contact material.

During gravitating passage of contact material of the character described downward through the pipe or conduit J, a stratifying operation occurs whereby the smaller pieces of material settle toward the bottom surface thereof. As a result, the contact material, as it reaches the lower end portion of said pipe J, has assumed a condition wherein the fines are at and immediately adjacent the bottom surface thereof while, upwardly from this bottom surface, the pieces of contact material progressively increase in size. In accordance with the invention, a classifying system or arrangement is provided which receives the contact material, after passage thereof from the lower end of the pipe J, and guides it into the upper end of the housing A in a selective manner to thereby modify the aforesaid non-uniform size distribution of the contact material in the conduit J and cause distribution thereof in a desired and improved manner horizontally across said housing A.

For the purpose described above, reference is to be had to Figs. 2, 3, and 4 wherein I have shown a plurality of duplicate passage-forming members, such as tubular frustums which, respectively, are of right-angle, rectangular pyramidal configuration, each of these frustums, in the form of the invention herein shown, defining a funnel K utilizable as hereinafter described. As illustrated in Figs. 2 and 3, the upper surfaces of all of the funnels K may coincide with a horizontal plane with the respective converging surfaces thereof extending downwardly. In the form of the invention herein illustrated, although not necessarily, the funnels K are grouped and suit-

ably secured to each other to form a grate or frame L having oblong rectangular configuration, this grate L, in the example shown, being defined by four longitudinal rows of funnels a1, a2, a3 and a4 with eight funnels in each row, the transverse rows of four funnels each being related to the longitudinal rows in right-angular relation. As hereinafter described, the contact material from the conduit J is discharged onto the upper surface of the grate L with the result that the funnels K guide independent streams thereof downwardly toward the top of the housing A. For purposes of explanation, the funnels K, Fig. 4, are designated by the numerals 1, 2, 3 and 4. Thus, there are eight funnels bearing the numeral 1, eight funnels bearing the numeral 2, and so on.

As regards the longitudinal funnel rows a1 and a2, it will be observed (except for the funnels 1 at the respective ends of said rows) that the funnels 1, 2, 3 and 4 of the row a2 are staggered or offset toward the left, Fig. 4, with respect to the respective funnels 1, 2, 3 and 4 of the row a1, the funnels being thus staggered or offset a distance corresponding with the length of any one of the duplicate funnels at the top surface thereof. It will also be observed that this staggered or offset funnel arrangement exists between correspondingly identified funnels of the rows a3 and a2 together with those of rows a4 and a3. Thus, as indicated by the lines d, Fig. 4, there are a plurality of spaced rows of the funnel 1, 2, 3 and 4 which are diagonally related to the longitudinal axis of the grate L.

In accordance with the invention, a group of attached receptacles M are disposed below and suitably secured to the aforesaid grate L diagonally as regards the longitudinal axis thereof in the same sense as described above with respect to the diagonal relation of the staggered funnels. For purposes of explanation, these receptacles are designated by the reference characters 1a, 2a, 3a and 4a, Fig. 5. Thus, there are three receptacles M bearing the reference character 1a, three receptacles bearing the reference character 2a and three receptacles bearing the reference character 3a. In addition, there are two receptacles M bearing the reference character 4a. As shown in Fig. 5, the bottom wall of each receptacle M comprises a discharge passage m utilizable as hereinafter described.

When the receptacles M are properly positioned in the described diagonal relation, all of the funnels 1 communicate only with the receptacles 1a, all of the funnels 2 communicate only with the receptacles 2a, all of the funnels 3 communicate only with the receptacles 3a and all of the funnels 4 communicate only with the receptacles 4a. Thus, in the form of the invention herein shown, all of the contact material traversing thirty-two of the funnels F passes into eleven receptacles M.

Further in accordance with the invention, a group of attached containers N, Figs. 6 and 7, having sloping bottom wall surfaces are disposed below and suitably secured to the aforesaid receptacles M, these containers extending in parallel relation with respect to the hereinbefore described rows of funnels a1, a2, etc. and being designated by the respective reference characters 1b, 2b, 3b and 4b. From a consideration of Figs. 5 and 6, it will be evident that the passages m of all of the receptacles 1a are disposed above the container 1b, that the passages m of all of the receptacles 2a are disposed

above the container 2b, that the passages m of all of the receptacles 3a are disposed above the container 3b and that the passages m of all of the receptacles 4a are disposed above the container 4b. Thus, in the form of the invention herein shown, all of the contact material traversing eleven of the receptacles M passes into four of the containers N.

Still further, in accordance with the invention, a group of pipes P are disposed below and suitably secured to the aforesaid containers N. These pipes are designated by the respective reference characters 1c, 2c, 3c and 4c and the the upper ends thereof communicate, respectively, with the containers 1b, 2b, 3b and 4b.

As shown in Fig. 1a, the pipes P extend through the upper wall of the housing A preferably in uniformly spaced relation as illustrated.

In view of the foregoing, it will be understood that the receptacles M and the containers N define passages extending between the funnels K and the respective pipes P. More particularly, due to the described receptacle-container arrangement, all of the funnels 1 communicate only with the pipe 1c, all of the funnels 2 communicate only with the pipe 2c, all of the funnels 3 communicate only with the pipe 3c and all of the funnels 4 communicate only with the pipe 4c. Accordingly, all of and only the contact material traversing the group of funnels 1 arrives at the pipe 1c, all of and only the contact material traversing the group of funnels 2 arrives at the pipe 2c, and so on.

In the form of the invention herein disclosed, the aforesaid group of funnels 1, which are connected only to the pipe 1c, consists of two funnels 1 in each of the funnel rows a1, a2, a3 and a4. It is a feature of the invention, as shown in Fig. 4, that the funnels 1 of each group thereof are spaced in the same relation (the same distance apart) longitudinally along the grate L, this holding true as regards each of the funnel rows a1, a2, etc. Similarly, the same uniform spaced relation exists between individual funnels of the groups of funnels 2, 3 and 4.

Referring particularly to Figs. 2 and 2a, the lower end of the hereinbefore described pipe J is shown as having secured thereto an elongated nozzle or mouthpiece R which is disposed in a plane at right-angles to the plane of said pipe J. As will be noted, the upper nozzle portion forms substantially a continuation of the pipe J while diverging from opposite, respective sides thereof. Secured within said nozzle portion are a plurality of diverging vanes or web members r which may terminate at the upper surface of the vertical nozzle end portion.

During operation of the system herein described, the buckets of the elevator 1 successively discharge contact material into the upper end of the pipe J, each charge thereof gravitating downwardly through said pipe J and then through the aforesaid nozzle R. By the nozzle vanes r, the contact material is directed or guided toward the grate L and caused to flow laterally across the grate to form a supported horizontal mass in which the material is horizontally stratified, as contrasted to the vertical stratification occurring in discharge pipe J. That is, the material is transposed from a mass in which the particle-size gradation is vertical to one in which the gradation is horizontal. In Fig. 4a, I have shown a typical outline taken by the contact material as it engages the upper surface of said grate L after passage thereof from the

nozzle R. From a comparison of the total areas of the respective funnels 1, 2, 3, and 4 which are covered by contact material, it clearly appears that the entire amount of such contact material is apportioned substantially equally between the respective groups of funnels which are within the outline referred to above. Further, this same relation exists for different outlines taken by the contact material provided that, in each instance, it extends at least nearly to the ends and sides of the grate L in the general manner shown in Fig. 4a.

It was hereinbefore explained that, during passage thereof through the conduit J, the contact material stratifies in the sense that the fines settle to the bottom conduit surface from which the size of the pieces of contact material progressively increase in an upward direction. Passage of the contact material through the nozzle R changes the configuration of the moving stream of contact material from that imposed by the pipe J to that imposed by the nozzle R together with its vanes r but is without any particular effect on the stratification pattern. Therefore, by reason of the fact that the plane of the nozzle R is at right-angles to the plane of the pipe J, it results that the contact material, when it engages the upper surface of the grate L, is stratified generally as shown by the shade lines in Fig. 4a wherein the light shade lines indicate the fines while the progressively heavier shade lines indicate the progressively larger pieces. With a stratification pattern of this character, the contact material which enters any group of funnels has substantially the same range of size distribution as that which enters each of the other groups of funnels.

Accordingly, by my invention, streams of contact material, which are substantially equal in quantity, traverse the respective groups of funnels and pass to the respective pipes 1c, 2c, 3c, 4c and each of these streams has substantially the same range of size distribution as regards the pieces of material having unequal size. A classifying operation of this character occurs for two reasons. It is due, first, to the staggered or offset relation which, in the respective funnel rows a1, a2, a3, and a4, exists between the group of funnels 1, the groups of funnels 2, and so on and, second, it is due to the fact that the funnels of each group thereof are spaced in the same relation longitudinally along the grate L.

As stated above, the pipes 1c, 2c, 3c and 4c, hereinafter referred to as the "pipes P," extend into the upper part of the housing A and, by these pipes, streams of contact material having the characteristics referred to immediately above are admitted thereto. As shown in Fig. 1a, the housing A is square in horizontal section and the discharge ends of said pipes P should be disposed in uniformly spaced relation with respect to each other and with respect to the housing wall structure. Therefore, in a horizontal plane coinciding with the discharge ends of the aforesaid pipes, the contact material is distributed substantially uniformly, as regards quantity and range of size distribution of the pieces thereof, in each of four symmetrical zones as defined by the discharge ends of the respective pipes P. This is advantageous for the reasons hereinafter stated.

Preferably, as shown in Figs. 1 and 1a, a horizontal tube sheet S is supported interiorly of the housing A a suitable distance below the ends of the pipes P. A plurality of tubes T open

through and depend from the tube sheet S and a group of these tubes, preferably four, are symmetrically related to each of the pipes P, the diameter of each of said tubes T being suitably reduced compared with that of each of the pipes P.

During regeneration in the housing A, the rate of withdrawal of contact material therefrom by way of the conduit G is suitably selected so that the contact material, at the lower ends of the pipes P and the tubes T, assumes and retains conical configuration generally as indicated in Fig. 1.

With an arrangement of the character described, each group of the tubes T distributes the contact material passing thereto from the associated pipe P substantially uniformly throughout approximately one-quarter of the total horizontal cross-sectional area of the housing A. As stated above, the contact material is distributed substantially uniformly, as regards quantity and range of size distribution of the pieces thereof, in each of the four zones defined by the discharge ends of the pipes P. By reason of the described action of each group of the tubes T with respect to the contact material issuing from each associated pipe P, it results that the aforesaid uniform distribution of the contact material is maintained to substantial extent throughout a plane extending horizontally through the housing A. Further, due to the fact that the contact material gravitates generally in a vertical direction through the housing I, the last named condition of uniform distribution persists throughout the vertical height of the housing A. This is highly advantageous.

Thus, should fine and coarse contact material be concentrated to substantial extent in different respective zones extending vertically through the housing A, the regenerating medium admitted thereto by the engagers C would traverse the coarse material zones to substantially greater extent than the fine material zones. As a result, the regenerating action in the material zones would be insufficient to effect proper removal of the carbonaceous deposit whereas, in the coarse material zones, the regenerating action would be magnified with resultant overheating and production of undesired hot-spots. By my invention, the contact material is not concentrated by size classes or in vertical strata to any substantial extent and, therefore, the regenerating operation proceeds in a desired manner. This insures substantially uniform regeneration of all of the contact material and prevents development of temperatures sufficiently high to damage the contact material or metallic parts of the housing A and associated apparatus.

It is true that, in the conical piles of contact material beneath the pipes P and tubes T, minor stratification of the contact material may occur and this is reflected by some non-uniformity in size distribution of the contact material in the downwardly moving bed thereof. However, this is insufficient to prevent satisfactory regeneration as described above and this is due to the fact that, when the contact material is admitted to the housing A, it is, as stated, distributed substantially uniformly, as regards quantity and range of size distribution, at the discharge ends of the pipes P.

The arrangement described above as comprising the pipes P, the tube sheet S and the tubes T relates to an important feature of the invention. However, in connection therewith, it shall

be understood that there is to be no limitation to the exact arrangement as disclosed and that any suitable number of these pipes and tubes, or equivalent may be utilized for the purpose stated.

Neither is the invention to be limited to introduction of the contact material into a regenerating housing which is square in horizontal section. As well, the housing A may have other suitable configuration and, if desired, it may be utilized for conducting any desired reaction adapted to proceed in the presence of gravitating contact material which is substantially uniformly distributed in accordance with the invention.

In the previous description, the grate L has been described as disposed in a horizontal position. It may be otherwise positioned and the contact material may be supplied thereto in any suitable or desired manner. Thus, for example, the grate L may be supported in inclined relation adjacent the upper end of the elevator I so as to receive charges of contact material directly from the elevator buckets.

As regards the classifier of the invention, it will be understood that there may be any suitable number of the funnels K or equivalent passage-forming members and, likewise, there may be any suitable number of outlet pipes P. Obviously, various equivalent arrangements may be utilized for connecting the aforesaid funnels K, or equivalent, in desired grouped relation to the pipes P. Increase in number of the funnels accompanied by decrease in size thereof improves the efficiency of the classifier as regards its intended functions.

The funnels, or equivalent, may be grouped otherwise than as disclosed and desired a single row thereof (instead of the four rows a1, a2, a3 and a4) may be connected in groups to the outlet pipes P in accordance with the general disclosure of this application. In connection with this simplified phase of the invention, the grate L may be omitted and, if so, the stratified material may be discharged directly onto the receptacles M, Fig. 7, which then serve as the grate and generally in classified manner as hereinbefore described pass the material to the containers N and then to the pipes P. As will be understood, the planes of the respective receptacles M may be parallel to the plane of the pipe J, or at some acute angle, preferably substantially less than a right angle, with respect thereto, the latter being indicated on the drawing.

In view of the foregoing description, it will be understood that I have disclosed a preferred system as shown in Figs. 2 and 3 which comprises the funnels K, and a simplified system as shown in Fig. 7 in which said funnels are omitted. Either system, as regards material which is charged thereto in stratified condition, functions to eliminate the stratified pattern and cause the material, in each of the pipes P, to have substantially the same range of size distribution as regards the pieces of material. Obviously, the material from the pipes P, for any desired purpose, may be combined in a single pipe or receptacle and, if so, the apparatus of my invention operates merely as an arrangement for de-stratifying previously stratified material. Unless otherwise limited, the appended claims shall be interpreted along the lines noted immediately above.

As hereinbefore stated, an important applica-

tion of the invention centers around an arrangement for classifying contact material which is discharged into engagement with the grate L in stratified condition. In this connection, it shall be understood that there is to be no restriction of the invention to any particular stratified pattern.

While adapted particularly to an arrangement for classifying contact material of the general character hereinbefore described, it will be understood by those skilled in the art that the invention is not to be thus limited. Thus, from a broader aspect, the invention relates to the classification of small pieces of other types of solid material having unequal size.

If desired and as shown in Figs. 1, 2 and 3, the outer wall structure defining the containers N may be extended in housing-forming relation, as indicated at N1, upwardly and around the receptacles M, the funnels K, the nozzle R and the lower end of the pipe J. Or, any other suitable housing may be provided for these parts as desired.

Obviously many modifications and variations of the invention as hereinbefore set forth may be made without departing from the spirit and scope thereof and therefore only such limitations should be imposed as are indicated in the appended claims.

I claim:

1. In a system of the character described, a group of pipes, a grate defining a plurality of side-by-side passages arranged in rows extending in right-angular relation, and means for connecting to the respective pipes groups of said passages extending in one direction along said grate, the passages in each of a plurality of groups thereof being spaced in the same relation, a plurality of the groups of passages in adjacent rows thereof being staggered uniformly with respect to each other.

2. In a system of the character described, a group of pipes, a grate defining a plurality of side-by-side passages having substantially duplicate peripheral configuration and arranged in rows extending in right-angular relation, and means for connecting to the respective pipes groups of said passages extending in one direction along said grate, the passages of all of the groups thereof being spaced in the same relation, all of the groups of passages in adjacent respective rows thereof being staggered uniformly with respect to each other.

3. In combination, a housing through which gravitates a moving bed of contact material formed from small pieces of such material having unequal size ranging down to fines, means for improving uniformity of distribution of the contact material, as regards size of the pieces thereof, in planes extending horizontally through said housing at different respective levels, said means comprising pipes extending through the top housing wall with the discharge ends thereof disposed substantially in uniform spaced relation with respect to each other, said pipes being traversed by streams of contact material containing, respectively, substantially equal quantities of such contact material and having substantially the same range of size distribution as regards the pieces of material, a tube sheet positioned horizontally below said pipes, and groups of tubes opening through and depending from said tube sheet, said groups of tubes being arranged in symmetrical relation as regards the respective pipes, the tubes of each

group being arranged in symmetrical relation with respect to each other.

4. In a system for classifying small pieces of solid material having unequal size, means from which such material is discharged while stratified to form a pattern conforming with gradation in size of the constituent pieces of material, and means defining a classifying zone into which the stratified material is admitted for passage therethrough, said classifying zone being constructed and arranged to separate the stratified material into streams of material containing, respectively, substantially equal quantities of such material and having substantially

15 the same range of size distribution as regards the pieces of material, said classifying zone comprising a grate which receives the material from said first named means, said grate being constructed and arranged to define a plurality of side-by-side passages traversed, respectively, by portions of said material, said classifying zone further comprising a plurality of receptacles arranged in side-by-side relation, each receptacle receiving material only from selected groups of said passages.

5. In a system for classifying small pieces of solid material having unequal size, means from which such material is discharged while stratified to form a pattern conforming with gradation in size of the constituent pieces of material, and means defining a classifying zone into which the stratified material is admitted for passage therethrough, said classifying zone being constructed and arranged to separate the

30 stratified material into streams of material containing, respectively, substantially equal quantities of such material and having substantially the same range of size distribution as regards the pieces of material, said classifying zone comprising a grate which receives the material from said first named means, said grate being constructed and arranged to define a plurality of side-by-side passages traversed, respectively, by portions of said material, said classifying zone further comprising a plurality of receptacles arranged in side-by-side relation, each receptacle receiving material only from selected groups of said

35 passages, said classifying zone further comprising a plurality of receptacles arranged in side-by-side relation, each receptacle receiving material only from selected groups of said

40 groups of said passages, said classifying zone further comprising a plurality of receptacles arranged in side-by-side relation, each receptacle receiving material only from selected groups of said

45 groups of said passages, said classifying zone further comprising a plurality of receptacles arranged in side-by-side relation, each receptacle receiving material only from selected groups of said

50 groups of said passages, said classifying zone further comprising a plurality of receptacles arranged in side-by-side relation, each receptacle receiving material only from selected groups of said

55 groups of said passages, said classifying zone further comprising a plurality of receptacles arranged in side-by-side relation, each receptacle receiving material only from selected groups of said

60 groups of said passages, said classifying zone further comprising a plurality of receptacles arranged in side-by-side relation, each receptacle receiving material only from selected groups of said

65 groups of said passages, said classifying zone further comprising a plurality of receptacles arranged in side-by-side relation, each receptacle receiving material only from selected groups of said

70 groups of said passages, said classifying zone further comprising a plurality of receptacles arranged in side-by-side relation, each receptacle receiving material only from selected groups of said

75 groups of said passages, said classifying zone further comprising

a plurality of containers arranged in side-by-side relation, each container receiving material only from selected groups of said receptacles, and a plurality of pipes connected, respectively, to said containers.

7. In a hydrocarbon conversion system in which solid contact material of unequal particle-size is passed downwardly in a vertically stratified confined stream into a contact zone wherein said material gravitates as a compact moving bed, the method of effecting substantially uniform particle-size distribution of said material across said bed which comprises the steps of passing said material from said confined stream onto a horizontal downwardly moving bed in laterally directed flow, thereby causing a horizontal stratification of material in said horizontal bed, withdrawing material from said horizontal bed in parallel zones extending transversely across said horizontal stratification pattern to form a plurality of confined streams of said material, grouping said confined streams into progressively recurrent series and collecting material from correspond-

10 ing units of each group to form a plurality of streams each containing contact material having substantially uniform particle-size distribution, passing said streams of collected material

5 into said contact zone and depositing the same onto the bed therein at uniformly distributed discharge points.
